(57) **CLAIM**

The ornamental design for an adjustable stand assembly, as shown and described.

DESCRIPTION

FIG. 1 is a perspective view of an adjustable stand assembly showing my new design in a fully assembled state of use; FIG. 2 is a top view thereof;

FIG. 3 is a front view thereof;

FIG. 4 is a rear view thereof;

FIG. 5 is a right side view thereof;

FIG. 6 is a left side thereof; and

FIG. 7 is a bottom view thereof;

FIG. 8 is a top view of a base portion of the adjustable stand assembly of FIG. 1 shown separate from the assembly for clarity of disclosure;

FIG. 9 is a front view thereof;

FIG. 10 is a rear view thereof;

FIG. 11 is a right side view thereof;

FIG. 12 is a left side thereof; and

FIG. 13 is a bottom view thereof;

FIG. 14 is a top view of the slider portion of the adjustable stand assembly of FIG. 1 shown separate from the assembly for clarity of disclosure;

FIG. 15 is a bottom view thereof;

FIG. 16 is a right side view thereof;

FIG. 17 is a left side thereof;

FIG. 18 is a front view thereof; and

FIG. 19 is a rear view thereof;

FIG. 20 is a front view of the fastener portion of the adjustable stand assembly of FIG. 1 shown separate from the assembly for clarity of disclosure;

FIG. 21 is a rear view thereof;

FIG. 22 is a right side view thereof;

FIG. 23 is a left side thereof;

FIG. 24 is a top view thereof; and

FIG. 25 is a bottom view thereof.

The broken lines shown in the drawings represent portions of the adjustable stand assembly and form no part of the claimed invention.

1 Claim, 13 Drawing Sheets
